UNITED STATES PATENT OFFICE.

STEVEN G. DAVIS, OF PERRYSVILLE, INDIANA.

CROSSING.

Application filed January 13, 1927. Serial No. 160,917.

The present invention relates to a highway crossing for railway tracks, the primary object of the invention being to provide a highway crossing embodying removable sections 5 so that sections of the highway may be removed to facilitate repairing of the railway track.

Another important object of the invention is to provide a device of this character which 10 may be clamped into position on the rails and held in such position against displacement by the usual vibrations of a railway track directed thereto by the passing of trains thereover.

With the foregoing and other objects in view which will appear as the description proceeds, the invention resides in the combination and arrangement of parts and in the details of construction hereinafter described 20 and claimed, it being understood that changes in the precise embodiment of the invention herein disclosed, may be made within the scope of what is claimed, without departing from the spirit of the invention.

Referring to the drawings:

Figure 1 is a plan view of a highway crossing constructed in accordance with the invention.

Figure 2 is a sectional view taken on line

30 2—2 of Figure 1.

Figure 3 is a sectional view taken on line 3—3 of Figure 1.

Figure 4 is a sectional view taken on line 4—4 of Figure 1.

Referring to the drawings in detail, the device includes supporting blocks 5 which are secured to the ties of the track that support the rails at the highway, and as shown, these supporting blocks have their upper 35 surfaces inclined as clearly shown by Figures 2 and 3 of the drawings, so that the outer sections 6, will be supported at angles for vehicles to pass upwardly over the rails.

Secured to the bases of the rails of the track at the highway crossing, are clamps 7 that are provided with threaded shanks 8 on which the nuts 9 operate, the clamps 7 being shown as gripping the rails while the nuts 9 draw the clamps into close engagement 45 with the rails and engage the opposite edges of the bases of the rails to secure the clamp in position.

At the outer end of each shank 8 is a pivoted link 10 which provides a keeper, to be 50 engaged by the hook member 11 associated therewith, the hook members 11 being se-

cured to the under surfaces of the outer sections 6.

Mounted on the upper surfaces of these outer sections are blocks 12 which are formed with obliquely disposed threaded bores to accommodate the threaded bolts 13 that are adapted to pass under the treads of the rails as shown by Figure 2 to hold the outer sections 6 downwardly and prevent the inner 65 edges thereof from lifting.

Upstanding ears 14 are formed on the clamps and are provided with openings to receive bolts 15 that also pass through the links 16 of the main supporting member of 70 the highway crossing. Pivoted members 17 have connection with the links and are formed with openings to receive the rods 18 that also pass through the bars 19 that provide means for holding the rods 18 in 75 spaced relation with each other and at the same time permitting free pivotal movement thereof.

The links 16 provide means for supporting 80 the planks 20 that are secured to the links in any suitable manner, while the rods 18 cooperate with the hook members 21 secured to the undersurfaces of the central planks 22 of the highway crossing, for securing the central planks in position.

In order that the central planks will be prevented from upward movement, upon the passing of a vehicle over the highway crossing, pivoted bars 23 are provided and are secured to one of the planks 20, the bars 23 having elongated openings to permit them to be fitted over the keepers 24 of the opposite plank 20 where bolts are passed therethrough, as shown by Figure 1 of the drawings.

Mounted on the ties and disposed between the rails of the track are supporting bars 25 that are provided with notches in which the rods 18 rest, the portions of the members 25 between the notches, acting as supporting 95 surfaces for the surface planks of the highway crossing.

From the foregoing it will be seen that should it be desired to repair the track under the highway crossing, at the outer sides of the rails, it will only be necessary to loosen the bolts 13, whereupon the section carrying the bolts 13 may be swung upwardly giving free access to the parts thereunder.

Should it be desired to repair the central portion of the track or that portion of the

track between the rails, the bars 23 may be removed whereupon the central portion of the highway crossing may be elevated or removed from the track entirely.

5 In view of the foregoing construction, the highway crossing may be readily removed or replaced, and the track construction thereunder repaired with facility.

10 While I have shown and described the crossing as used on a highway crossing a railway track at right angles, it is to be understood that the principle of the invention may be embodied in a crossing wherein a highway crosses a railway track at an oblique angle, without departing from the 15 spirit of the invention.

I claim:

1. A highway crossing for railway tracks embodying supporting bars having notches 20 and secured to the ties of the railway track, clamping members secured to the rails, rods supported by the clamping members and resting in the notches, outer highway sections having hook members, means for 25 movably connecting the hook members to the clamping members, center planks forming a part of the highway crossing and having hooks engaging the rods to hold the planks in position, and means engaging the 30 upper surfaces of the planks for holding the planks against upward movement.

2. A highway crossing for railway tracks embodying clamping members to be secured to the rails of the railway track, said clamping 35 members embodying extensions, links pivotally connected with the extensions,

highway sections having hooks positioned within the links to removably secure the highway sections to the extensions, highway plank sections pivotally connected with the 40 clamping members, and removable plank sections supported between the rails.

3. A highway crossing for railway tracks embodying clamping members adapted to be clamped to the rails of the track, supporting 45 members on the ties of the track, links carried by the clamping members, outer highway sections, means carried by the outer highway sections and cooperating with the links for removably securing the outer highway sections in position, and removable center highway planks supported between the 50 rails of the track.

4. A highway crossing for railway tracks embodying clamping members adapted to be 55 clamped to the bases of the rails of the track, outer highway sections, means for removably supporting the outer highway sections on the clamping members, means carried by the outer highway sections and engaging the 60 rails for holding the outer highway sections in position, links connected with the clamping members, rods extending longitudinally of the railway track and supported by the links, central highway plank sections, and 65 means cooperating with the rods and carried by the plank sections for securing the plank sections in position.

In testimony that I claim the foregoing as my own, I have hereto affixed my signature. 70

STEVEN G. DAVIS.
